STRIP FORMING APPARATUS

Calhoun Norton, Chicago, Ill., assignor to Arens Controls, Inc., Chicago, Ill., a corporation of Illinois

Application April 23, 1942, Serial No. 440,265

22 Claims. (CL 153—67)

This invention relates to strip forming apparatus such, for example, as apparatus for coiling wire and the like.

It is an object of the invention to provide strip forming apparatus of improved construction and operating characteristics, the invention having particular application to apparatus of the type wherein the metal strip, which may comprise a wire or the like, is coiled or otherwise formed about an elongated mandrel.

More specifically, one of the objects of the present invention is to provide improved control structures for apparatus of the type defined, which control structures include means for automatically disabling the operating mechanism of the machine at the end of the processing operation and also in the event of improper operation of the strip feeding means or in the event the tension within the strip exceeds a predetermined amount.

A further object of the invention is to provide improved means for feeding the metal strip to be formed to the forming station, whereby to impart to the strip more uniform tension at all times, and thereby improving the uniformity and quality of the processed structures.

A still further object of the invention is to provide improved support means for the mandrel and for the processed structures whereby to permit the fabrication of the strip into long lengths and into structures of uniform characteristics and quality.

Various other objects, advantages and features of the invention will appear from the following specification when taken in connection with the accompanying drawings wherein certain preferred embodiments are set forth for purposes of illustration.

In the drawings, wherein like reference numerals refer to like parts throughout:

Fig. 1 is a general assembly view in perspective of a metal strip forming apparatus, specifically in the form of a wire coiling machine, constructed in accordance with and embodying the principles of the invention;

Fig. 2 is a side view of the structure shown in Fig. 1, more particularly illustrating portions of the head frame structure;

Fig. 3 is a diagrammatic view illustrating the character of the work adapted to be performed by the machine;

Fig. 4 is a detail, perspective view of the traveling carriage or strip fabricating structure;

Fig. 5 is a detail, perspective view illustrating a latch member associated with the cut-off means of the carriage;

Fig. 6 is a transverse, sectional view through the carriage structure on the line 6—6 of Fig. 4, particularly illustrating the means for feeding the strip to the forming station;

Fig. 7 is a transverse, sectional view through the carriage on the line 7—7 of Fig. 4, and showing the cut-off means;

Fig. 8 is a top view of the structure shown in Fig. 7;

Fig. 9 is a detail, perspective view of a portion of the machine bed, showing one of the mandrel supporting elements;

Fig. 10 is a detail, perspective view of a part of the strip feeding means;

Fig. 11 is a side view illustrating a modified form of head frame structure;

Figs. 12 and 13 are partial views of the feeding means and carriage, respectively, as adapted for use with the head frame structure illustrated in Fig. 11; and

Fig. 14 is a wiring diagram for the structures shown in Figs. 11, 12 and 13.

In the drawings a machine for coiling wire around an elongated mandrel is specifically illustrated, and certain features of the invention are particularly adapted for use in a machine of this character. It is to be understood, however, that the invention in various of its aspects is adapted for metal strip forming apparatus generally, and apart from the specific embodiment illustrated, the strip being of any desired specific type, and fabricated in any desired manner. The specific machine illustrated in the drawings comprises an apparatus for forming elongated wire coils to be utilized in the manufacture of flexible transmission cables, either as shiftable transmission coils or as sheath coils.

Referring more particularly to the drawings, and first to Figs. 1 and 2 thereof, the structure illustrated comprises a head frame generally indicated by the numeral 10 and an end frame 11 connected by an elongated bed 12. A plurality of forming carriages 13 and 14 are longitudinally reciprocable on the bed, between the head and end frames, during the operation of the machine.

More specifically, the head frame 10 comprises a casing 15 housing a prime mover in the form of an electric motor 16 which furnishes the power for driving the machine. The motor is connected to drive a main drive shaft 17 which, by means of a pair of belts or the like 18 and 19, is arranged to drive an upper stub shaft 20 and a lower stub shaft 21, suitably journaled in the housing. The stub shaft 20 has a pulley wheel

22 keyed thereto and a second pulley wheel 23 loosely mounted on the shaft, the arrangement being such that when the belt 18 is positioned for engagement with the pulley 22 the shaft 20 will be driven, whereas when the belt is shifted to the left as seen in Fig. 2, for engagement with the pulley 23, the shaft 20 will be disengaged from its driving connections. Similarly, the stub shaft 21 carries a pulley 24 keyed thereto and another pulley 25 loosely mounted thereon, the belt 19 being shiftable from the pulley 24 to the left as seen in Fig. 2 for engagement with the idler pulley 25 whereby to disconnect the drive connections to the shaft. The means for shifting the belts will be hereinafter described.

A chuck 28 is connected to the end of the stub shaft 20, for rotation therewith, and a chuck 29 is similarly connected to the end of the stub shaft 21. These chucks support elongated mandrel wires 30 and 31 extending between the head frame and the end frame of the machine. The other ends of the mandrel wires are connected, respectively, to chucks 32 and 33 carried by the end frame. The end frame comprises a series of uprights 34 and cross braces 35, arranged to support a pair of plates 36 and 37 in which the chucks 32 and 33 are loosely mounted. The arrangement is such that as the stub shafts 20 and 21 are driven, the chucks and mandrels secured thereto will be rotated at relatively high speed. The chucks are adapted to releasably grip the mandrel wires, as will be readily understood, whereby the mandrel wires may be removed for replacement, substitution, or for the removal of the fabricated work therefrom.

Referring to Figs. 1, 2 and 9, it will be seen that the bed 12 comprises a series of uprights 40, of which any suitable number may be provided depending upon the length of the bed structure, which, in certain instances, may extend for a distance of a hundred feet or more. The uprights carry a series of laterally extending support platforms 41 forming the supports for a pair of elongated track members 42 and 43 forming a track structure for the upper carriage 13, and a pair of similar track members 44 and 45 forming a track structure for the lower carriage 14. As best shown in Figs. 1 and 9, each lateral support structure 41 has associated therewith a mandrel engaging member 48, pivotally mounted upon a bracket 49 secured to the support by means of a pivot 50, and urged yieldingly upwardly by means of a compression spring 51 supported from a cross brace 52. The pivoted members 48 constitute vibration dampening means for the mandrel wires, and to that end are provided with elongated troughs 53 within which the mandrel wires are to be engaged, and with tapered end portions 54 and 55 adapted to be engaged by the carriages 13 and 14 in their longitudinal movements. The arrangement is such that normally the members 48 are yieldingly urged upwardly by their associated springs 51 into light engagement with the mandrel wires 30 and 31, thereby serving to prevent undue vibration of the wires, which vibration may tend to interfere with the fabrication or forming processes of the machine, particularly in installations where the mandrels are of extended length. At the same time the carriages 13 and 14 in their longitudinal movements, and upon engagement with the tapered portions 54 and 55 of the members 48, readily move said members downwardly from operative position to permit the necessary movements of the carriage structures. Limiting

means is associated with the pivots 50 for limiting the upward pivotal movements of the members 48 substantially to a horizontal position, as shown in Fig. 9, whereby to prevent undue upward movement of the members upon removal of the mandrel wires or the slight lifting thereof by the carriages during the fabrication processes.

The structure of the carriages is best illustrated in Figs. 1 and 4-8. Both carriages are the same, and a description of one will suffice for both. As shown in Fig. 4, the carriage 13 comprises a base or frame plate 57 having secured to its lower face a pair of angles 58 and 59 adapted to engage the tracks 42 and 43 to facilitate the longitudinal carriage movements. During the strip fabrication or specifically the wire coiling operations, the carriage is moved to the right as seen in Figs. 1 and 4, and the trailing edge of the base plate 57 is provided with a bracket 60 having at its end a trough portion 61 adapted to engage the mandrel and the wire coiled thereon, whereby to dampen mandrel vibration for the reason and in the manner previously discussed in reference to the vibration damping members 48 associated with the bed structure.

In Fig. 4 the metal strip to be fabricated is indicated by the numeral 63, this strip being in the form of a wire to be coiled around the mandrel 30, in a particular embodiment of the invention illustrated. The wire 63 is received by the carriage from the feeding means of the machine, later to be described, first passing through a cutter device to a support pedestal or guide 64 through which it is transmitted to a flexible sheath 65. As best shown in Fig. 6, this sheath delivers the wire over a pair of guide pins 66 and 67 into the fabricating or forming fixture. This fixture comprises a frame member 68 fixed to the base plate 57 of the carriage, and a lever member 69 pivotally mounted as indicated at 70 upon a pair of brackets 71 and 72 secured to the frame member 68. The inner end of the frame member 68 carries a forming or fabricating jaw 73, and the inner end of the lever 69 similarly carries a fabricating or forming jaw 74. A compression spring 75 normally urges the lever 69 clockwise about its pivot 70, whereby to cause the work to be gripped between the forming jaws 73 and 74, the clockwise movement of the lever being limited by an adjustment nut 76. The wire 63 passes between the brackets 71 and 72, and then between the jaws 73 and 74 and onto the mandrel 30. The arrangement is such that as the mandrel 30 is rotated by the driving motor 16, the wire 63 will be caused to be coiled around the mandrel at the forming station in a manner best illustrated in Fig. 3, the wire being drawn to the fabricating, forming or coiling station through the guiding support pedestal 64, the flexible sheath 65, and the guide pins 66 and 67. As the coiling progresses, the wire 63 will be continuously urged against the bracket 71, causing the carriage to be continuously moved to the right, as seen in Figs. 1 and 4, during the operation. The initial position of the carriages is to the extreme left, adjacent the head frame 10, and at the starting of the coiling operation the end of the wire 63 may be suitably anchored within openings 78 in the chucks 28 or 29 as the case may be.

Referring further to Fig. 4, it will be seen that there is a combined oiling and guide block 80 carried by the carriage base 57, engageable with the mandrel just in advance of the coiling sta-

tion. This guide block is associated with an oil reservoir 81 having a delivery spout 82 for delivering oil or other suitable lubricant onto the mandrel wire. A valve 83 controls the delivery of the lubricant from the reservoir 81. When the valve is in its vertical position, as illustrated in solid lines in Fig. 4, the oil or lubricant will be delivered from the spout 82. At the end of the coiling operation and as the carriages reach the end of their travel, the valve is adapted to be engaged by an abutment such as indicated at 84 in Fig. 1, whereby to move the valve to its dotted line position as illustrated in Fig. 4, shutting off the supply of lubricant.

The cutting device or cut-off means through which the wire 63 passes before reaching the guide pedestal 64 comprises a frame member 86 having at one end thereof a stationary shearing head as illustrated at 87. The construction of the cutting device is best illustrated in Figs. 4, 7 and 8. This head is provided with a plurality of openings as indicated at 88 of different size, and of different shape, if desired, to receive the appropriately sized wires 63. Coaxially mounted with the stationary shearing head, upon a pivot 89, is a movable shearing head 90, provided with a series of openings 91 corresponding to and in alinement with the openings 88 of the stationary shearing head, when the parts are in normal position. The movable shearing head 90 is provided with an extension 92 formed on its end with a series of gear teeth adapted for engagement with gear teeth formed on the end of a lever 93 pivoted as indicated at 94 on the cutter frame 86. As the lever 93 is operated, the shearing head 90 will be moved relative to the stationary head 87 whereby to effect a cutting operation upon the wire 63.

A coiled tension spring 95, Fig. 1, is provided for urging the lever 93 counterclockwise as seen in Fig. 7 to effect such shearing operation, but normally movement of the lever is prevented by a latch lever 96 pivoted upon the stationary shearing head as indicated at 97 and having a notched end portion 98 engageable with a pin 99 secured to the lever 93. The structure is illustrated in Figs. 4, 5 and 7. At the end of the coiling operation, the end 100 of the latch lever 96 is adapted to engage a release abutment such as indicated at 101 in Fig. 1, whereby to release the lever 93 for operation. Cut-off means is thus provided for severing the wire or metal strip being fabricated, at the end of the forming operation, such cut-off means being automatically operable as the traveling work carriage reaches a predetermined position and after a predetermined length of work has been formed. The operating lever 93 for the cut-off means is also manually operable at any time, as may be desired, upon release of the latch lever 96.

The feeding means for feeding the wire 63 to the carriages is best illustrated in Figs. 1 and 10. As shown, a supply drum or reel 105 supplies the wire for the upper carriage 13, whereas a drum or reel 106 supplies the wire for the lower carriage. The feeding means for both carriages are the same, and a description of one will suffice for both.

Referring to the feeding means for the upper carriage 13, it will be seen that the wire is transmitted from the supply reel to a flexible sheath 107 of suitable structure, preferably in the form of a wire coil or the like as best shown in Fig. 10.

The wire 63 loosely passes through this sheath. One end of the sheath is fixed to a bracket 108

5 mounted on one of the uprights of the end frame, and the other end of the sheath is fixed to a bracket 109 mounted on a platform 110 arranged for slight shiftable movement longitudinally of the machine bed 12. To this end the platform carries a pair of angles 111 and 112 supported by and movable longitudinally of the bed tracks 42 and 43. An opening, as indicated at 113, Fig. 1, is provided in the plate 36 through which the sheath 107 loosely passes.

10 A rod 115 extends longitudinally of the machine bed, the rod being adapted for longitudinal shiftable movement within its supporting brackets 116 carried by the track structure. One end 15 of this rod adjustably carries an abutment member 117 adapted to be engaged by the platform 110 as it is shifted a predetermined distance to the left as seen in Figs. 1 and 10. The other end of the rod carries a fork 118, Fig. 2, adapted to engage the driving belt 18, and to shift the belt 20 between the pulleys 22 and 23. A tension spring 119 secured at one end to the platform 110 and at its other end to the end frame 11 tends to urge the platform to the right as seen in Figs. 1 25 and 10 against a suitable stop member carried by the machine bed, as indicated at 120. It will be noted that due to the angular or curved disposition of the sheath 107, any pulling force upon the wire 63 will tend to cause the outlet end of 30 the sheath and the platform 110 to move to the left against the action of the spring 119.

35 The supply reel 105 is freely mounted on its axis, as indicated at 121, and normally freely supplies the wire 63 through the flexible sheath 107 to the carriage 13. Only a relatively slight pulling force upon the wire 63 is required to overcome the frictional resistance to movement of the supply drum and associated parts. This force is sufficient to move the platform 110 away 40 from the stop 120, but insufficient to move the platform against the action of spring 119 into engagement with the abutment 117. Accordingly, during normal feeding operation the platform 110 fluctuates somewhat between its abutment and its stop. This movement is insufficient to operate the control rod 115, but it tends 45 to impart a more uniform drag or pulling force to the wire 63 in its movement to the forming carriage. In other words, the arrangement of 50 the feeding means is such that regardless of slight variations in force which would normally be encountered in removing the wire 63 from its supply reel, such as variations in frictional resistance in movement of the reel, or slight 55 snags in the position of the wire on the reel, the feeding means is so arranged that these fluctuations in resistance are compensated for and a resultant uniform frictional drag is imparted to the wire. Accordingly, the wire 63 is under 60 uniform tension at all times in its transmission to the forming carriage, this uniform tension insuring uniformity in the coiling or other fabricating operation being performed. The fabricated work may thus be held to a uniform size 65 and quality.

70 Should the tension required to remove the wire from the supply reel exceed a predetermined amount, as for example if the wire should become badly snagged or otherwise jammed, the platform 110 moves sufficiently to the left to engage the abutment member 117 of the control rod 115, thereby shifting the belt 18, Fig. 2, and stopping the rotation of the mandrel. It will be noted that this disabling of the operating mechanism takes place without the cutting of the

wire 63, or other permanent disorganization of the parts, and after the difficulty in connection with the feeding of the wire has been corrected, operation may be resumed by the reverse shifting of the control rod 115.

The mode of operation of the machine is believed to be clear from what has heretofore been set forth. More specifically, a wire coiling operation is initiated by moving the carriage to the left as seen in Fig. 1, the end of the wire 63 being drawn into position and inserted in the opening 78 in the operating chuck 28. Movement of the control rod 115 initiates rotation of the mandrel, and the operation automatically continues until the carriage reaches the end frame, at which time the release abutments 84 and 101 automatically operate to terminate the action of the oiling means and to cut the wire 63. As the end of the wire is drawn around the mandrel into completely coiled condition, the movement of the carriage automatically stops. At all times during the forming operation the mandrel is retained from undue vibration. The feeding means yieldably operates to insure a uniform tension within the wire 63, and in the event that this tension exceeds a predetermined maximum the operating mechanism of the machine is immediately disabled. Operation may thereafter be resumed as desired. Also, it will be noted that the control rod 115 extends the entire length of the machine so that it may be operated by the operator at any position.

It is to be understood that the manner of operation of both carriages 13 and 14 is the same.

In Figs. 11, 12, 13 and 14 a modified embodiment of the invention is illustrated. Referring to Fig. 11, in this instance the head frame 10a is provided with separate driving motors 130 and 131 for propelling the stub shafts 20a and 21a associated, respectively, with the mandrels. These motors are independent and are provided with independent energizing circuits. Referring to Fig. 12, in this instance the platform 110a of the feeding mechanism is adapted upon undergoing a predetermined movement to the left, to operate an arm 132 of an electric switch 133 arranged in the energizing circuit for its associated motor. The arrangement is such that the switch is opened when the arm 132 is shifted to the left by the platform. Also in this instance, referring to Fig. 13, the frame member 68a of the forming means of the carriage is provided with an electric switch structure 134 controlled by the presence or absence of the wire or strip 63 to be fabricated. More particularly, the member 68a is provided with a cut-away section 135 into which a spring-pressed switch arm 136 is adapted to move, away from its co-operating contact 137. When the wire 63 is present, the arm 136 is maintained upwardly in engagement with the contact 137 to maintain the switch 134 closed. When the wire 63 terminates, either at the end of the forming operation when it is severed by the cut-off means, or in the event the wire otherwise runs out during the forming operation, the switch arm 136 will drop into the notch 135 and open the switch.

Fig. 14 diagrammatically illustrates the energizing circuit for the motor 130, and it will be seen that the switches 133 and 134 are arranged in series in the circuit along with a manually operable main control switch 140. Closing of the switch 140, assuming switches 133 and 134 to be closed, energizes the motor 130 and causes rotation of the mandrel. During the forming opera-

tion should the tension within the wire 63 exceed a predetermined amount, switch 133 will operate to deenergize the motor. Also, if during the forming operation the supply of wire should run out, and at the end of the operation upon operation of the cutting means associated with the carriage, switch 134 will operate to deenergize the motor and stop the mandrel. It will be noted that switch 134 is located in immediate juxtaposition to the wire coiling station, so that the switch does not operate until the forming of the wire has been substantially completed.

The machine herein shown is similar in certain respects to that shown in my copending application, Serial No. 442,347, filed May 9, 1942. Certain features of the machine shown herein, in their broader aspects, are claimed in said copending application.

It is obvious that various changes may be made in the specific embodiments of the invention set forth for purposes of illustration without departing from the spirit of the invention. The invention is accordingly not to be limited to the specific embodiments shown and described, but only as indicated in the following claims.

The invention is hereby claimed as follows:

1. A metal strip forming apparatus comprising means for forming a metal strip into a series of concentric convolutions, said means including a member bodily shiftable axially of said convolutions during the forming operation, said member being shifted by the strip as it is formed, a rigid track structure for supporting said member during its shiftable movements, and cutter means shiftable with said member and automatically operable as said member reaches a predetermined shifted position to sever the strip to thereby disable the effectiveness of said forming means.

40. 2. A metal strip forming apparatus comprising an elongated rotatable mandrel, means for forming a metal strip around the mandrel in an extended series of convolutions extending helically of the mandrel, said means including a carriage bodily shiftable axially of the mandrel during the forming operation, said carriage being shifted by the strip as it is formed, means including a rigid track structure for guiding the carriage in its shiftable movements, and means automatically operable as said carriage reaches a predetermined shifted position for disabling the effectiveness of said forming means while the mandrel remains in operation.

3. A metal strip forming apparatus comprising an elongated mandrel, means for forming a metal strip around the mandrel in an extended series of concentric convolutions, said means including a carriage bodily shiftable axially of the mandrel during the forming operation, a rigid track structure for guiding the carriage in its shiftable movements, and cut-off means automatically operable as the carriage reaches a predetermined position longitudinally of the mandrel for severing said strip.

65. 4. A metal strip forming apparatus as defined in claim 3, wherein said cut-off means comprises a pair of relatively shiftable cutting members carried by the carriage and through which the strip is adapted to be passed, spring means tending to relatively shift said members to cutting position, a latch for inhibiting the operation of the spring, and abutment means for disabling the latch.

75. 5. A metal strip forming apparatus comprising means for forming a metal strip into an extended

series of coaxial convolutions, said forming means comprising a member bodily shiftable axially of said convolutions during the forming operation, a rigid track structure along which said member is shifted, and means automatically operable for disabling the effectiveness of said forming means when the tension required to transmit the strip to the forming means exceeds a predetermined amount.

6. A metal strip forming apparatus comprising means for forming a metal strip into an extended series of coaxial convolutions, feeding means for feeding the metal strip to the forming means, power means for operating the forming means, and means automatically operable for disabling the power means when the tension required to transmit the strip to the forming means exceeds a predetermined amount.

7. A metal strip forming apparatus comprising means for forming a metal strip into an extended series of coaxial convolutions, feeding means for feeding the metal strip to the forming means, power means, connections between the power means and the forming means, and means automatically operable for disabling said connections when the tension required to transmit the strip to the forming means exceeds a predetermined amount.

8. A metal strip forming apparatus comprising means for forming a metal strip into an extended series of coaxial convolutions, feeding means for feeding the metal strip to the forming means, power means including an electric motor for driving the forming means, and control means for deenergizing said motor, said control means being controlled by the tension required to transmit the strip to the forming means.

9. A metal strip forming apparatus comprising means for forming a metal strip into an extended series of concentric convolutions, said means including a forming member adapted to receive the strip from a source of supply and bodily shiftable axially of said convolutions during the forming operation, said member being shifted by the strip as it is formed, power means for driving said forming means, means automatically operable as said member reaches a predetermined shifted position for disabling said power means, and means for disabling the power means upon termination of the strip in its transmission to the forming member.

10. A metal strip forming apparatus comprising means for forming a metal strip into an extended series of concentric convolutions, said means including a member bodily shiftable axially of said convolutions during the forming operation, a rigid track structure for guiding said member in its shiftable movements, means automatically operable as said member reaches a predetermined shifted position for disabling the effectiveness of said forming means, and means operable during the forming operation controlled by the tension required to transmit the strip to the forming means for disabling the effectiveness of said forming means in the event the strip tension exceeds a predetermined amount.

11. A metal strip forming apparatus comprising means for forming a metal strip into an extended series of concentric convolutions, power means for driving said forming means, means automatically operable after a predetermined number of convolutions have been formed to disable said power means, and means operable during the forming operation and controlled by the

tension required to transmit the strip to the forming means for disabling the power means in the event the strip tension exceeds a predetermined amount.

5 12. A metal strip forming apparatus comprising an elongated mandrel, means for forming a metal strip around the mandrel in an extended series of coaxial convolutions, said means including a member bodily shiftable axially of the mandrel during the forming operation, said member being shifted by the strip as it is formed, and control means extending axially of the mandrel and substantially along the entire length thereof for controlling the starting and stopping of said forming means.

10 13. A metal strip forming apparatus comprising means for fabricating a metal strip into a predetermined series of formations, supply means for the strip, feeding means for feeding the strip from the supply means to the forming means, and control means associated with the feeding means for imparting a uniform tension to the strip regardless of fluctuations in resistance encountered in removing the strip from the supply means,

15 25 said control means comprising a flexible sheath of curved shape through which the strip is adapted to be passed, and means for yieldably mounting one end of the sheath so that the sheath is shiftable in accordance with variations in the tension of the strip.

30 14. A metal strip forming apparatus comprising an elongated mandrel, means for forming a metal strip around the mandrel, said forming means including a carriage bodily shiftable axially of the mandrel during the forming operation, supply means for the strip, feeding means for feeding the strip from the supply means to the carriage, and control means associated with said feeding means for imparting a uniform tension to the strip regardless of fluctuations in resistance encountered in withdrawing the strip from the supply means.

35 15. A metal strip forming apparatus as defined in claim 14, wherein said control means comprises a flexible sheath of curved shape through which said strip is adapted to be passed, and means for yieldably mounting one end of the sheath so that the sheath is shiftable in accordance with variations in the tension of the strip.

40 50 16. A metal strip forming apparatus comprising means for fabricating a metal strip into a predetermined series of formations, supply means for the strip, feeding means for feeding the strip from the supply means to the forming means, and control means associated with the feeding means for imparting a uniform tension to the strip regardless of fluctuations in resistance encountered in removing the strip from the supply means, said control means also being operable when the tension in the strip exceeds a predetermined amount to disable said forming means.

45 55 60 65 17. A metal strip forming apparatus comprising an elongated rotatable mandrel, means for forming a metal strip around said mandrel, said means including a carriage bodily shiftable axially of the mandrel during the forming operation, an elongated bed along which the mandrel is adapted to extend, and means carried by the bed engageable with the mandrel at predetermined points for preventing undue vibration thereof, said means being automatically shiftable to accommodate the shiftable movements of the carriage.

70 75 18. A metal strip forming apparatus comprising an elongated frame carrying an elongated

mandrel, means for forming a metal strip around the mandrel, said means including a carriage shiftable axially of the frame along the mandrel during the forming operation, lubricating means carried by the carriage for lubricating the mandrel during the shiftable movements of the carriage, and abutment means fixed to the frame at a predetermined position longitudinally of the mandrel for controlling the operation of said lubricating means.

19. A metal strip forming apparatus comprising an elongated rotatable mandrel, power means for rotating the mandrel, means for forming a metal strip around the mandrel in an extended series of concentric convolutions, said means including a carriage bodily shiftable axially of the mandrel during the forming operations, said carriage being shifted by the strip as it is formed, feeding means for feeding the metal strip to the carriage, and means for automatically operable for disabling the power means when the tension required to transmit the strip to the carriage exceeds a predetermined amount.

20. A metal strip forming apparatus comprising an elongated rotatable mandrel, power means for rotating the mandrel, means for forming a metal strip around the mandrel in an extended series of concentric convolutions, said means including a carriage bodily shiftable axially of the mandrel during the forming operations, said car-

riage being shifted by the strip as it is formed, feeding means for feeding the metal strip to the carriage, and means automatically operable for disabling the power means upon termination of the strip in its transmission to the carriage.

21. A metal strip forming apparatus comprising means for forming a metal strip into a pre-determined series of formations, supply means for the strip, feeding means for feeding the strip from the supply means to the forming means, a flexible sheath of curved shape through which the strip is adapted to be passed in its transmission from the supply means to the forming means, means for fixedly mounting the end of said sheath adjacent the supply means, a shiftable member adapted to be connected to the other end of said sheath, the tension of the strip being adapted to shift said member in one direction, and spring means normally tending to urge said member in the opposite direction, the movements of said member serving to equalize variations in the tension of the strip in its transmission from the supply means to the forming means.

22. A metal strip forming apparatus as defined in claim 21, wherein control means is provided for disabling the forming means, said control means being operated by the movement of said member a predetermined amount against the action of said spring.
